ROTARY MUSIC HOLDER

Warren Frederick Malpas, Roselle Park, N.J.

Application August 27, 1947, Serial No. 770,861

1 Claim. (Cl. 45—61)

1

This invention relates to music holders and more particularly to rotary music holders adapted for attachment to some manually held musical instruments.

The need for facilitating the turning of music while engaged in the operation of some manually held musical instruments has long been felt.

It is an object of the instant invention to provide a music holder capable of being rotated so that the music on either side of the sheet is quickly available.

A further object is to provide a compact light weight device the operation of which is both simple and positive.

Other objects of the instant invention will become apparent in the course of the following specification.

In the attainment of these objectives, the rotary music holder is formed at the top of opposing clamp members under closing tension adapted for insertion of the music. The opposing clamp members are attached at the top of a downwardly turned rotatable support the base of which is designed for insertion in the usual co-acting aperture provided or which may be provided for mounting music holders on musical instruments of the type described. The downwardly turned rotatable support comprises a top and bottom member with the top of the bottom member rotatably inserted in the base of the top member. A slot substantially at the base of the top member is so formed that the rotation of the opposing clamp members is limited to the amount of rotation within the requirements of the performer. Furthermore, the mechanism is so devised that only a partial manual movement of the opposing clamp members is necessary for a rotation through a straight angle. This is accomplished by inserting a spring within the top member of the downwardly turned support adapted to press against the top of the bottom member rotatably inserted therein. The arrangement devised insures rapid and positive rotation when desired and prevents undesirable rotation.

The invention will appear more clearly from the following detailed description when taken in connection with the accompanying drawings showing by way of example preferred embodiments of the inventive idea.

In the drawings:

Figure 1 shows a front elevational view of the rotary music holder constructed in accordance with the principles of this invention.

Figure 2 is a sectional view through the line 2—2 of Figure 1.

2

Figure 3 is a top view of the rotary music holder.

Figure 4 is a fragmentary view of the downwardly turned support for the music holder showing the rotation mechanism enlarged.

Referring now in greater detail to the drawings in which like reference numerals indicate like parts, reference numeral 10 indicates the rotary music holder, 11 the clamp, 12 the top member of the downwardly turned support, 13 the bottom member of the downwardly turned support, and 14 the revolving mechanism.

The clamp 11 is formed of the two opposing clamp members 15 and 16 formed integral with and substantially perpendicular to the base members 17 adapted for insertion of the music therebetween. By bringing the opposing clamp members 15 and 16 substantially to points at the top minimum interference with the music is encountered.

At the base of the opposing clamp members 15 and 16, the spring member 18 is turned upwardly along each of the longitudinal edges with the slot 19a therebetween in order to provide means for insertion of the opposing clamp members 15 and 16 of the clamp 11 therebetween.

At either side of the spring member 18, the slits 19 are formed for insertion therethrough of the handle members 20 formed integral with and in the plane of the opposing clamp members 15 and 16. By pressing the handle members 20 together with the fingers, the opposing clamp members 15 and 16 are moved apart against the closing tension of the spring member 18.

The horizontal member 21 with upturned edges adapted to be superimposed on the spring member 18 has cut out portions 22 (Fig. 1) for insertion against the inside surface portions of the handle members 20 thereby providing substantial support for said opposing clamp members 15 and 16. The spring member 18 and horizontal member 21 are removably attached to the top of the subsequently described top member 12 of the downwardly turned support.

The top member 12 is a partially hollow tube with inside tap 23 at the top adapted for insertion of the screw 24 through aligned apertures in the spring member 18 and the horizontal member 21.

Near the top of the top member 12, on the inside, is the coil spring 25 adapted to be compressed therein by the top of the subsequently described bottom member 13.

The bottom member 13 of the downwardly turned support is adapted to be inserted in the

bottom of the top support 12 at one end and at the opposite end in a co-acting attaching means on the musical instrument (not shown).

Substantially at the base of the top member 13 is the slot 26 curved upwardly and downwardly, over substantially 180°. The pin 27 inserted into the top of the bottom member 13 under tension of the coil spring 25 permits the top support 12 to be rotated only through some 180°. The pressure of the coil spring 25 on the top of the bottom member 13 forces the pin 27 against the lower periphery of the slot 26 obviating any movement of the rotary music holder except under a substantial force that must actuate it at least upwardly to the maximum point 15 of elevation whereupon the coil spring 25 will in general finish the operation of rotation.

It is apparent the specific illustrations shown above have been given by way of illustration and not by way of limitation and that the structures above described are subject to wide variation and modification without departing from the scope or intent of the invention, all of which variations and modifications are to be included within the scope of the present invention.

What is claimed is:

In a rotary music holder having a clamp, a top member adapted to receive said clamp on one end and having a longitudinal bore formed

therein extending from its lower end to a point intermediate the ends thereof, said top member having a transverse slot formed therein adjacent said lower end, a bottom member therein adjacent said lower end, the ends of said slot being substantially 180° apart, said slot being curved upwardly intermediate its ends, a bottom member having its upper portion in said bore and rotatable therein, a pin adjacent the upper end of said bottom member and extending through said slot, and resilient means in said bore urging said bottom member downwardly.
